VAPOR CONDENSING APPARATUS

Charles C. Peake, Media, Pa., and Franklin J. Eubank, Glendora, N.J., assignors to Westinghouse Electric Corporation, Pittsburgh, Pa., a corporation of Pennsylvania

Filed July 14, 1964, Ser. No. 382,471

11 Claims. (Cl. 60—95)

This invention relates to vapor condensing apparatus, more particularly to apparatus for condensing the exhaust vapor from a vapor motivated turbine power plant, and has for an object to provide improved apparatus of this type and method of operation thereof.

When a vapor condenser is employed to condense the exhaust vapor from a plurality of turbines in a closed cycle multi-unit vapor turbine power plant, it is often advantageous to divide the condenser into the same number of condensing zones or chambers as the turbines that it serves. Also, for economic reasons the condenser tubes are arranged in a single bundle extending through all of the chambers. Hence as the coolant liquid flows through the tubes from chamber to chamber, it becomes progressively heated by absorption of heat from the condensing vapor, and the exhaust vapor in each chamber is subjected to coolant liquid at a different temperature and thus condensed at a different pressure and temperature.

Condensers of the above type are known as "zoned" condensers and attain a lower average condensing pressure and temperature than unzoned or undivided condensers, thereby providing improved thermal efficiency in the vapor cycle of the power plant.

Heretofore, in "zoned" condensers, the condensate from the higher pressure condensing zones or chambers has been conducted successively to the lower pressure condensing chambers and allowed to flash into vapor and then cool to the saturation temperature corresponding to the pressure in each of the lower pressure chambers. The condensate from all of the chambers was ultimately collected in the lowest pressure chamber and finally withdrawn from this chamber at the correspondingly low saturation temperature prevailing therein.

When zoned condensing apparatus is employed in a closed cycle power plant having a regenerative feed liquid heating system for preheating the condensate before admission to the vapor generator for vaporization, the feed liquid heaters employ heating vapor extracted from the turbines.

An object of the invention is to provide vapor condensing apparatus of the zoned type arranged and operated in such a manner that the condensate from the lower pressure chambers is introduced to a higher pressure chamber for heating purposes, thereby to yield condensate from the apparatus at substantially said higher temperature.

Still another object is to provide in a vapor turbine power plant having a regenerative feed liquid heating system, zones condensing apparatus arranged and operated in a manner to yield feed liquid for the vapor generator at the highest attainable initial temperature.

Briefly, there is provided apparatus for condensing the exhaust vapor from a plurality of, for example, two condensing turbines in a closed cycle vapor turbine power plant and divided into an equal plurality of condensing zones or chambers, one for each turbine associated therewith. The coolant fluid conducting tubes extend through all of the chambers, so that, as the tubes absorb heat from the vapor during the condensation process, the coolant fluid is progressively heated. The attendant saturation or condensation pressures and temperatures attained in the chambers thereby differ, with the chamber associated with the hotter portion of the tubes having the higher pressure and temperature, and the chamber

2

associated with the colder portion of the tubes having the lower pressure and temperature.

In accordance with the invention, the cooler condensate from the lower pressure and temperature chamber is pumped to at least the same pressure as that prevailing in the higher pressure and temperature chamber and then admitted into the upper portion of the higher pressure chamber by suitable spraying means. Accordingly, the thus pumped condensate is heated to a higher temperature by the vapor in the higher pressure chamber and then withdrawn with the condensate from the higher pressure chamber and directed through one or more feed liquid heaters before delivery to the vapor generator.

The feed liquid heaters employ hot motive vapor extracted from the turbines for heating the feed liquid to the desired vapor generator inlet temperature. Hence, with the invention less extracted vapor is required by the heaters to heat the feed liquid, and more motive vapor is available to generate turbine output power, with an appreciable increase in efficiency in the vapor cycle of the power plant.

The above and the objects are effected by the invention as will be apparent from the following description and claims taken in connection with the accompanying drawings, forming a part of this application, in which:

FIGURE 1 is a schematic diagram of a closed cycle vapor turbine power plant system of the regenerative feed liquid heating type with vapor condensing apparatus in accordance with the invention; and

FIG. 2 is a vertical elevational view, partly in section, of a portion of the power plant system shown in FIG. 1 and illustrating an embodiment of the condensing apparatus.

Referring to the drawings in detail, in FIGURE 1 there is shown schematically, a closed cycle vapor turbine power plant system, generally designated 10, of the regenerative feed liquid heating type and having vapor condensing apparatus, generally indicated 12, in accordance with the invention.

The invention may be employed in conjunction with a turbine power plant system employing any condensable vapor, for example, steam, ammonia, etc. Henceforth the terms "steam" and "water" will be employed for simplicity and facility of understanding.

The power plant 10, as illustrated, is provided with an HP (high pressure) steam turbine unit 13, an IP (intermediate pressure) steam turbine unit 14 and a plurality of (three in this instance) LP (low pressure) steam turbine units 15, 16 and 17. The turbine units 13, 14, 15, 16 and 17 are connected in tandem to each other by suitable shaft couplings 18, so that the total power output of the turbines is taken off at the output shaft 19 of the LP unit 17 and, by a suitable coupling 20, the power output shaft 19 is employed to drive a suitable single load, for example, an electrical generator 21.

Hot motive steam to motivate the units 13 to 17, inclusive, is provided by a suitable steam generator 23 connected to the HP unit 13 by a suitable steam supply conduit 24. Accordingly, the steam generated by the steam generator 23 is directed through the steam supply conduit 24 to the HP unit 13 and after expansion therein it is directed by a suitable conduit 25 to the IP unit 14. After expansion in the IP unit 14, the steam is directed to the three LP units 15, 16 and 17 by conduit structure 26 having parallel branches 27, 28 and 29, respectively connected to the LP units 15, 16, and 17.

The LP units 15, 16 and 17 are substantially of the same size and type and, as illustrated, may be of the well known central admission, double opposed flow type. Accordingly, with reference to the LP unit 15, for example, the steam is admitted thereto at the center by the conduit 27 and thence divides, with one half of the steam flowing to

the right for expansion through the right half expansion portion 15a and the remaining half being directed toward the left and expanded through the left-hand expansion portion 15b and is exhausted therefrom in two streams, as indicated by the arrows 30 and 31. The remaining two LP units 16 and 17 are arranged and operated in the same manner as the LP unit 15 and need not be further described.

After the steam is exhausted from the LP units 15, 16 and 17, it is condensed in the condensing apparatus 12, in accordance with the invention and subsequently to be described in full detail, and then directed to a plurality of feed water heaters 34, 35 and 36 by a suitable conduit 37, for reheating before return to the steam generator 23 for re-vaporization, thereby completing the closed loop or cycle.

The feed water heaters 34, 35 and 36 are of the regenerative heat exchanging type (well known in the art) and are employed to preheat the condensate flowing therethrough by way of the conduit 37. These heaters may be substantially identical in structure. Accordingly, only the feed water heater 34 will be described in detail.

The feed water heater 34 comprises a shell structure 38 defining a compartment 39 and within the compartment 39 there is provided a suitable heat exchanger tube structure 40. Steam is extracted from the units 15, 16 and 17, after partial expansion therein, by three pairs of conduits 41 and directed to the compartment 39 of the feed water heater 34 by a common conduit 42. Accordingly, as the feed water is directed through the heat exchanger tube structure 40, it is initially heated to a degree by heat exchanged therewith and the resulting condensate formed by the steam admitted thereto is returned to the feed water conduit structure 37 at a point upstream of the heater 34 by suitable conduit structure 45.

In a similar manner, the feed water heater 35 is effective to heat the feed water flowing therethrough to an additional and higher degree, by steam extracted from the IP unit 14 and directed thereto by a suitable conduit 46, and the last or highest feed water heater 36 is effective to further heat the condensate flowing therethrough to the final or terminal value before admission to the steam generator 23, by employment of steam extracted from the HP unit 13 and directed thereto by suitable conduit structure 47.

The condensate forming in the feed water heater 36 is directed to the compartment of the upstream feed water heater 35 by suitable conduit structure 48 for re-flashing into steam, thereby to impart additional heat to the feed water flowing therethrough. The condensate resulting therefrom is directed to the upstream feed water heater 34 by a suitable conduit 49 for further feed water heating and then joins the condensate in the feed water heater 34. The condensate connecting arrangement of the feed water heaters 34, 35 and 36 illustrated in FIG. 1 and described above is well known in the art and is usually called feed water heater cascading.

As thus far described, the system is substantially conventional and well known in the art. Since the feed water heaters 34, 35 and 36 employ steam extracted from the units 13 to 17, inclusive, they divert some of the steam from the turbine units that would otherwise be employed to motivate the turbines and thereby provide more power at the output shaft 19. However, it has been found that the advantages of employing extracted steam from the units in the manner shown provides sufficient thermal advantages to the system to offset the loss of power obtained at the output shaft 19.

The extraction arrangements shown in FIG. 1 are merely representative and illustrated for explanation reasons only. That is, the steam for heating the feed water heaters may be extracted from the units 13 to 17 at any location in the expansion range and more or less feed water heaters may be employed than the three shown and described above, as well known in the art.

Referring now more particularly to FIG. 2, wherein the LP units 15, 16 and 17 are shown in more detail and illustrating the condensing apparatus 12 in accordance with the invention, it will be seen that the condensing apparatus 12 is employed in conjunction with all of the LP units 15, 16 and 17. The condensing apparatus 12 includes a suitable shell structure 50 coextensive with the exhaust outlets 51, 52 and 53 of the LP units 15, 16 and 17, respectively. Within the shell structure 50 there are provided partitions 54 and 55 which together with the shell structure 50 divide the latter into zones or chambers 56, 57 and 58, each of which is substantially pressure tight with respect to the other, although the partition 55 is provided with an opening 59 disposed at the lower end thereof and normally covered by a water level existing therein, as more fully to be explained subsequent hereto.

There is further provided a plurality or bundle of elongated tubes 60 coextensive with the shell 50 and extending through the partitions 55 and 54 and serving, by heat exchange, to condense the exhaust vapor from the LP unit 15 as indicated by the arrows 30 and 31 and from the LP units 16 and 17, as indicated by the arrows 30a, 31a and 30b, 31b, respectively.

Externally of the shell structure 50 there is provided an inlet water box 61 and an outlet water box 62. Water or other coolant fluid is admitted to the inlet water box 61 by a suitable conduit 63, then directed through the tubes 60 and finally discharged from the outlet water box 62 to a suitable discharge conduit 64. Since the tubes 60 are maintained in a cool state by the water flow therethrough, they are effective to condense the exhaust vapors admitted into the chambers 58, 57 and 56 in a well known manner, and the resulting condensate formed in each chamber drops to the bottom thereof as a rain and collects to a level shown at 65. It will be noted that the condensate level 65 in chamber 57 is above the opening 59. Hence, no vapor can escape through the outlet 59 from the chamber 57 to the chamber 58, in normal operation.

The lower portion of chamber 58 is provided with a condensate discharge outlet 67 connected to a suitable water pump 68 and discharge from the pump 68 is directed through a suitable conduit 69 to a suitable spray manifold 70 disposed in the upper portion of the chamber 56. The manifold 70 is provided with a plurality of apertures 71 effective to direct the water downwardly in a fine spray in commingling relation with the exhaust vapor admitted into the chamber 56 by the LP unit 15, thereby promoting intimate heat exchange relationship between the two.

The resulting condensate in chamber 56 is withdrawn therefrom through a suitable discharge outlet 73 disposed at the bottom of the shell structure 50 and communicating with a water pump 74, the outlet of which is connected to the conduit 37 (previously described). Further, the returning condensate from the feed water heaters in conduit 45 is admitted to the outlet 67 ahead of the pump 68, thereby to rejoin the condensate in the feed water conduit 37.

If desired, the water level 65 in the chamber 58 may be controlled by a suitable valve 75 controlled by a float structure 76 arranged to reduce the flow through the valve 75 when the liquid level falls below a preselected height, and to increase the flow when the liquid level exceeds a predetermined height. In a similar manner, the level of the condensate 65 in the chamber 56 may be controlled by a valve 77 and float 78 connected thereto in the same manner.

Method of operation

For facility of comprehension, in FIG. 1 steam flow is denoted by the dotted arrows, condensate and feed water is denoted by the solid arrows, and the coolant water is denoted by the arrows with tails.

In operation, the exhaust steam from the LP units 15,

16 and 17 is directed into the associated condenser chambers 56, 57 and 58 for condensation therein by heat exchange with the tubes 60 extending through the heat exchanger structure. Accordingly, the water flowing in the tubes 60 becomes progressively hotter from left to right, as when viewed as illustrated in FIG. 2, by absorption of the heat from the condensing vapor and, in view of this phenomenon, the condensate in chamber 58 is formed at a lower temperature and pressure value than in chamber 57 where the tube portions 60b are somewhat warmer than the tube portions 60a in the chamber 58. Accordingly, the ambient in chamber 57 is stabilized at a condensing pressure and temperature that is higher than that in chamber 58 and, similarly, the chamber 56 is maintained at a still higher condensing pressure and temperature by the tube portions 60c than the preceding two chambers 57 and 58. Hence, the condensate forming in chamber 56 is warmer than the condensate forming in chamber 57, and similarly, the condensate forming in chamber 57 is warmer than the condensate formed in chamber 58. Because of the pressure differential between chambers 57 and 58, the condensate forming in chamber 57 flows into the chamber 58 through the opening 59 with resulting re-boiling and release of some heat to chamber 58 because of the temperature difference. The condensate in chamber 58, together with the condensate flowing thereto from chamber 57, is withdrawn through the outlet 67 and pressurized by the pump 68, and then sprayed into the chamber 56 by the spray manifold 70. Since the water sprayed into the upper portion of the chamber 56 by the manifold 70 is at a lower temperature than the condensation temperature prevailing therein, as the water spray drops to the bottom of the chamber 56, it absorbs heat therefrom. The mixture is subsequently withdrawn through the outlet 73 by the pump 74 and directed to the feed water heaters by the conduit 37.

It will now be seen that all of the condensate formed in the condensing apparatus 12 is withdrawn therefrom at substantially the same temperature. Further, since the condensate from the lower temperature chambers 57 and 58 is admitted into the highest temperature chamber 56 for further heating before directing to the feed water heaters, all of the condensate is withdrawn from the condensing structure 12 at the highest prevailing temperature.

Since the condensate is directed to the feed water heaters at a higher value than heretofore, less extraction of steam from the turbine units is required than heretofore to heat the feed water in the feed water heating system to the temperature desired before admission to the steam generator 23. Accordingly, more of the motive steam may be gainfully employed in the turbine units to produce power at the output shaft 19.

The condenser apparatus 12 has been shown and described as a unitary structure, however, as illustrated schematically in FIG. 1, the three condensing chambers 56, 57 and 58 may be provided by separate and distinct shell structure and, similarly, the tube structure 60 need not be unitary, but may be divided into three interconnected groups to provide the tube portions 60a, 60b and 60c.

It will now be seen that the invention provides condensing apparatus of highly improved form and an improved method of operating condensing apparatus employed in conjunction with a closed cycle vapor turbine power plant system having a regenerative feed liquid heating system for preheating the condensate before admission to the steam generator.

It will further be seen that with the arrangement shown there is provided a condensing vapor turbine power plant operable at higher thermal efficiency than heretofore by condensing structure that is economical to manufacture and simple to employ.

Although in the embodiment shown, three double-flow LP units 15, 16 and 17 of the condensing type have been shown, it will be understood that more or less condensing turbine units may be employed and that they need not be of the double-flow type.

Although only one embodiment of the invention has been shown, it will be obvious to those skilled in the art that it is not so limited, but is susceptible of various other changes and modifications without departing from the spirit thereof.

What is claimed is:

1. The method of operating a vapor turbine power plant having at least two condensing turbines exhausting to vapor condensing apparatus at different pressures and temperatures,

said condensing apparatus having a first pressure and temperature condensing zone communicating with one turbine and a second and higher pressure and temperature condensing zone communicating with the other turbine; comprising pumping the condensate from the first condensing zone to said second zone, and spraying the thus pumped condensate into said second zone for reheating.

2. The method recited in claim 1 and further including

mixing the reheated condensate with the condensate in the second zone to provide feed liquid for a vapor generator, and

30 directing the resulting feed liquid to said vapor generator for evaporation into vapor for motivating the turbines.

3. The method recited in claim 1, and further including

35 directing coolant fluid first through the first condensing zone and then through the second condensing zone, thereby to maintain the difference in pressure and temperature between the condensing zones.

4. The method of operating a vapor turbine power

40 plant having at least three condensing turbines exhausting to vapor condensing apparatus, said condensing apparatus having first, second and third condensing zones, each communicating with an associated one of said turbines; comprising maintaining said first, second and third condensing zones at successively higher first, second and third pressures and temperatures,

directing the condensate from said second zone to said first zone into mixing relation with the condensate in said first zone,

50 pumping the resulting condensate mixture from said first zone to said third zone, and spraying the thus pumped condensate into said third zone for reheating.

5. The method recited in claim 4, and further comprising

55 directing the condensate from the third zone through at least one regenerative heater to further heat the condensate, and

60 then directing the condensate as feed water to a vapor generator for evaporation into vapor for motivating the turbines.

6. The method recited in claim 4, and further comprising

65 directing coolant fluid successively through the first, second and third condensing zones, thereby maintaining the first, second and third pressures and temperatures therein.

7. A vapor turbine power plant, comprising at least two condensing turbines, vapor condensing apparatus, said condensing apparatus having a first condensing chamber communicating with one of said turbines and a second condensing chamber communicating with the other of said turbines,

- means disposed in said first and second chambers for condensing the exhaust vapors from said turbines at different pressures and temperatures,
- means for pressurizing the condensate from the lower pressure and temperature chamber, and
- means for spraying the thus pressurized condensate into the higher pressure and temperature chamber for reheating purposes.
8. The structure recited in claim 7, and further comprising
- 10 a steam generator for providing motive vapor to the turbines,
- a regenerative heating system having a heater for heating feed liquid to said steam generator, and
- 15 means for directing the condensate from the higher pressure and temperature chamber to said heater as feed liquid.
9. Condensing apparatus for a condensing multi-unit vapor turbine power plant, comprising
- 20 shell structure defining at least two vapor condensing chambers,
- a bundle of coolant conducting tubes extending through said condensing chambers and defining a single coolant pass,
- 25 means for directing coolant liquid through said tubes, so that vapor in one of said chambers is condensed at a lower pressure and temperature than in the other of said chambers,
- means for pumping the condensate from said one chamber to the other chamber,
- 30 means in said other chamber for spraying the thus pumped condensate into the upper portion thereof, thereby to promote the absorption of heat by said condensate spray, and
- 35 means for withdrawing the combined condensate from said other chamber.
10. Condensing apparatus for a condensing multi-unit vapor turbine power plant, comprising
- 40 shell structure defining at least three juxtaposed vapor condensing chambers,
- a bundle of tubes for conducting coolant fluid through said chambers in a single pass,
- 45 inlet and outlet means for directing coolant liquid to and from said tubes, respectively, whereby vapor is condensed at successively higher pressures and temperatures in each of said chambers, with the chamber adjacent said inlet means being maintained at a lower pressure and temperature than the next adja-

- cent chamber and the chamber adjacent said outlet means being maintained at a higher pressure and temperature than said next adjacent chamber,
- means for directing the condensate from the next adjacent chamber to the chamber adjacent said inlet,
- means for pumping the condensate from the chamber adjacent said inlet to the chamber adjacent said outlet,
- means for admitting the thus pumped condensate in finely divided form into the chamber adjacent said outlet to promote absorption of heat thereby, and
- means for withdrawing the combined condensate from the chamber adjacent said outlet for steam generation purposes.
11. A vapor turbine power plant, comprising a first turbine unit,
- at least two condensing turbine units,
- said first unit operating at a higher pressure than said condensing units,
- vapor condensing apparatus,
- said condensing apparatus having a first condensing chamber communicating with one of said condensing turbines and a second condensing chamber communicating with the other of said condensing turbines,
- means disposed in said first and second chambers for condensing the exhaust vapors from said condensing turbines at different pressures and temperatures,
- means for pressurizing and pumping the condensate from the lower pressure and temperature chamber to the higher pressure and temperature chamber,
- means for spraying the thus pressurized condensate into the higher pressure and temperature chamber for reheating purposes,
- a steam generator for providing motive vapor to said turbines,
- a regenerative heating system having a heater for heating feed liquid to said steam generator,
- means for directing the condensate from the higher pressure and temperature chamber to said heater as feed liquid, and
- means for extracting a portion of the motive vapor from one of said turbines and directing it to said heater.
